UNITED STATES PATENT OFFICE.

ORVILLE L. M. HOOVER, OF DALLAS, TEXAS, ASSIGNOR OF ONE-HALF TO M. D. HOOVER,
OF DALLAS, TEXAS.

LIQUID OR GASEOUS FUEL BURNING FURNACE.

Application filed January 22, 1923. Serial No. 614,152.

To all whom it may concern:

Be it known that I, ORVILLE L. M. Hoover, citizen of the United States of America, residing at Dallas, in the county of Dallas 5 and State of Texas, have invented certain new and useful Improvements in Liquid or Gaseous Fuel Burning Furnaces, of which the following is a specification.

This invention relates to new and useful 10 improvements in liquid or gaseous fuel burning furnaces.

The object of the invention is to provide certain improvements in furnace forming the subject matter of my Letters Patent No. 15 1,370,446, issued March 1, 1921, and also to produce in such a furnace advantages making for efficiency and economy.

A particular object of the invention is to provide a superheating coil in the flues of 20 the pre-heating chamber, whereby the fuel is heated to a highly combustible condition prior to its introduction into the burner.

Another object is to provide dampers in the pre-heating flues instead of at the ports 25 between the pre-heating and combustion chambers, whereby a more efficient arrangement may be had and both dampers controlled by a single operating means.

A further object is to provide baffles in the 30 combustion chamber in connection with a fire arch at the forward end of the chamber, whereby the flame from the burner may more efficiently heat the boiler or still and any back or counter-acting drafts may be 35 controlled.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a longitudinal vertical sectional view,

Fig. 2 is a horizontal cross-sectional view on the line 2—2 of Fig. 1,

Fig. 3 is a plan view of the furnace,

Fig. 4 is a partial front elevation, and

Fig. 5 is a transverse sectional view on the line 5—5 of Fig. 3.

In the drawings, the numeral 10 design-

nates the front wall of a furnace housing, 11 the rear wall and 12 and 13 the side walls. These walls and the other parts of the furnace are to be constructed of such materials as are commonly used in the art. At the front of the furnace an arched opening 14 is provided in the front wall 10 at the center thereof.

A horizontal floor or partition 15 divides the housing into a preheating chamber below the floor and a combustion chamber above the floor, the proportions of which may vary in accordance with the requirements. A plurality of longitudinal baffle walls 16 extend from the bottom of the preheating chamber to the underside of the floor and are directed rearwardly from the front wall. These baffle walls are spaced 60 apart to form parallel air flues A, B, and C on each side of a central air flue D. Arcuate pockets 17 meet at a point relatively centrally of the flue D and connect the rear ends of the flues A, B, and C on each side.

The flues B, C, and D have their front ends open at the arch opening 14 so as to permit the passage of air thereinto. Air entering these flues will be drawn to the rear end of the pre-heating chamber and deflected 70 by the pockets 17 into the flues A. At the forward ends of the flues A, ports 18 in the floor 15 establish communication with the forward end of the combustion chamber. It will be seen that air entering the flues B, 75 C, and D will be thoroughly heated and circulated thru the pre-heating chamber. The rear ends of the baffle walls 16 may be stepped off toward the flues A in order to promote circulation.

The arched opening 14 extends above the floor 15 and a suitable oil or gas burner (not shown) extends thru said opening into the combustion chamber. A rearwardly inclined arch 19 spans the forward end of 85 the combustion chamber and has its ends anchored in the side walls 12 and 13 which latter may be built up to the proper height to support a horizontal boiler or still (not shown) above the combustion chamber. Transverse baffles 20 extending from the side walls are directed forwardly and intersect the forward ends of longitudinal baffles 21 extending rearwardly. The baffles

20 extend from the floor to the arch and the air currents admitted from the pre-heating chamber thru the ports 18 are deflected toward the center of the chamber under the 5 arch and are induced rearwardly into the flame of the burner which is projected into the flaring throat formed by the baffles 21. It will be seen that the arch 19 prevents back currents from the combustion chamber 10 whipping back over the baffles 20 and interfering with the circulation of the pre-heated air currents; also the currents admitted thru the ports 18 are compelled to pass into the throat instead of seeking a general escape 15 in the chamber.

In order to control the draft and the flow 20 of the pre-heated air currents I arrange dampers 22 transversely of the flues A centrally on a transverse rock shaft 23 mounted in bearing sleeves 24 supported in the walls 16, the ends of the shaft having bearings in the side walls 12 and 13. A T joint 25 is connected in the shaft in the flue D and has the rear end of a lever 26 pivoted in its depending member. The lever has a handle 27 outwardly of the opening 14 and is provided with notches 28 in its under edge for engaging over a bar 29 disposed transversely in the flue D. By moving the lever longitudinally 25 the dampers 22 are swung to obstruct the passage of air thru the flues A. When the dampers are vertical the said flues are entirely closed and by swinging said dampers to different inclinations the passage of air or draft of the furnace will be regulated thereby. The handle 27 is within easy reach of the engineer and the dampers may be readily adjusted.

While the preheating of the air currents 40 passing thru the flues, due to the heat radiation from the floor 15, is highly important and advantageous, a particular feature which makes for efficiency and economy, resides in a pair of fuel superheating coils 30 45 disposed in the flues B and C and looped into the rear ends of the flues A and curved around the pockets 17. Each coil is connected with a cut-off valve 31 connected with a pipe 32 for supplying oil, gas or other fluid fuel. Each coil enters the flue B and conveys the fuel fluid thru the flues B, pocket 17, rear end of flue A and returns it thru the pocket 17 and flue C. The discharge end of each coil extends thru the opening 14 and 50 is connected with an upwardly extending burner pipe 33. By this means the fuel fluid is heated to a highly combustible condition and makes for a hotter flame and a reduction in fuel consumption. The combustion 55 of the pre-heated air currents and the super-heated fuel makes a highly efficient furnace. In order to determine the temperature of the super-heated fuel fluid, a suitable indicating device 34 may be mounted on 60 the discharge end of each coil.

In operating the furnace, cool or fresh air is admitted to the flues B, C and D thru the opening 14 and caused to circulate around the baffle walls 16 and contact with the bottom of the floor 15, which latter is heated by the burner in the combustion chamber above. The air passing thru the pre-heating chamber is heated a maximum temperature and is conducted forwardly in the flues A to the ports 18. The heated air currents pass thru the port and are deflected toward the center of the chamber by the arch 19 and baffles 20. The passage of the air thru the ports, and thus the draft, may be controlled and regulated by manipulating 65 the dampers 22.

The air heated to its maximum pre-heated temperature is directed into the throat formed by the baffles 21 and promotes combustion in the chamber, whereby it is heated by the flame of the burner to its highest temperature and passes to the still or boiler with its maximum heating capacity. The fuel fluid which passed thru the coils 30 is super-heated and is thus supplied to the burner in a 70 highly combustible condition.

Various changes in the size and shape of the parts as well as modifications may be made within the scope of the appended claims.

What I claim, is:

1. In a furnace of the character described, a housing divided into superposed pre-heating and combustion chambers having communicating openings at their forward ends 100 at each side thereof, the bottom of the combustion chamber forming the top of the pre-heating chamber, the front wall of the housing having an air admitting opening communicating with the pre-heating chamber, longitudinal baffle walls in the pre-heating chamber forming air circulating flues, said flues communicating at their rear ends and the outermost flues connecting with the combustion chamber, draft controlling dampers arranged in the outside flues, means for operating the dampers, transverse baffles in the combustion chamber, a longitudinal throat extending rearwardly from the baffles, and an arch at the front end of the combustion chambers covering the baffles and the communicating openings between the chambers, the throat extending beyond the arch.

2. In a furnace of the character described, a housing divided into superposed pre-heating and combustion chambers having communicating openings at their forward ends 120 at each side thereof, the bottom of the combustion chamber forming the top of the pre-heating chamber, the front wall of the housing having an air admitting opening communicating with the pre-heating chamber forming air circulating flues, said flues communicating at their rear ends and the outer-

most flues connecting with the combustion chamber, draft controlling dampers arranged in the outside flues, means for operating the dampers, transverse baffles in the combustion chamber, a longitudinal throat extending rearwardly from the baffles, an arch at the front end of the combustion chambers covering the baffles and communicating openings between the chambers, the throat extending beyond the arch and super- 10 heating fuel fluid coils passing thru the flues of the pre-heating chamber.

In testimony whereof I affix my signature.

ORVILLE L. M. HOOVER.
